LUBRICATING DEVICE

Filed Oct. 17, 1925

UNITED STATES PATENT OFFICE

ARTHUR M. GREENE, JR., OF PRINCETON, NEW JERSEY, ASSIGNOR TO NATHAN MANUFACTURING COMPANY, OF NEW YORK, N. Y.

LUBRICATING DEVICE

Application filed October 17, 1925. Serial No. 63,038.

This invention relates generally to a device for feeding lubricant to the working parts of fluid-pressure operated apparatus.

It has heretofore been the practice to introduce oil into steam or other fluid pressure pipes and chambers in relatively large globules or drops with the result that the oil has been imperfectly distributed and irregularly applied to the pistons, valves and other working surfaces.

A general object of the invention is to provide means for introducing oil in a finely divided form or spray into the actuating fluid of a fluid-pressure operated engine, pump, compressor, or the like, so that the fine oil particles will be thoroughly distributed by the steam or other fluid on the various working surfaces needing lubrication.

The invention consists in the production of an atomizing effect on a mass of liquid lubricant which is brought about by causing steam or other fluid to travel at high velocity across an orifice forming a terminal for a passageway or duct containing the lubricant under pressure. A feature of the invention resides in the provision of a Venturi tube through which the steam which is to carry the lubricant is caused to flow to thereby produce in the moving column of steam a relatively high velocity such as will produce a limited lowering of pressure in the region surrounding the moving steam and the desired mixing effect at ports formed in the throat of the tube at the most constricted section thereof. The ports communicate with a conduit or passageway leading from the oil supply pump or other feeding device so that the steam traveling at high velocity through the constricted throat of the Venturi tube causes a flow of oil through the ports into the tube and atomizes or disintegrates it to produce a spray or finely divided condition thereof. The oil spray thus formed is carried with the stream of steam into the working chambers for distribution on the surfaces sought to be lubricated.

Other features of the invention will be hereinafter referred to.

In the drawings, in which a preferred embodiment of the invention has been selected for illustration,

Figure 1 is a view in side elevation of a portion of a steam engine and showing a lubricating apparatus embodying the invention and applied thereto.

Figure 2 is a view in vertical section and on an enlarged scale taken on the line 2—2 of Figure 1.

Referring to the drawings for a more detailed description of the invention, in Figure 1 there is shown the cylinder 10 of a steam engine with a steam chest 11 mounted thereon, a steam supply pipe 12 being provided through which steam passes from a boiler, not shown, into the steam chest 11 and from thence into the steam cylinder 10 to operate the reciprocating piston therein in a known manner.

The invention herein includes the provision of means for utilizing steam flowing from a manifold 13 to carry a charge of oil in a spray or finely divided form through feeding tubes 14, 15 and 16 into the steam space within the steam supply pipe 12, the steam chest 11, and the steam cylinder 10, respectively.

In order to convert the oil in the desired finely divided form for the necessary thorough distribution to all the working parts with which the oil-charged steam comes into contact, a Venturi tube structure is made use of through which steam is caused to flow from the manifold 13 to produce in said tube a velocity relatively higher than that at the entrance of the tube to create a reduced pressure condition in the region immediately surrounding the constricted portion of the moving stream. The constriction is such as to accomplish the desired velocity and is such that there is sufficient pressure at all times to prevent a suction of oil. To carry this into effect a Venturi tube 17 is mounted within a casing 18 mounted between a discharge orifice member 19 carried by the manifold 13 and one or other of the feed tubes 14, 15, or 16 already referred to.

In order to utilize the reduced area effect produced by the pressure condition immediately surrounding the constricted portion of the Venturi tube, a series of ports 20 are arranged to communicate with a chamber 21

surrounding the tube 17 and into which a passage 22 leads. The passage 22 terminates at a non-return or check valve structure 23 of any form placed at the upper terminal portion of a passageway 24 formed in a member 25 to which a terminal of a discharge oil pipe 26 is attached. The form shown is one of several terminal check valves which might be applied. The pipe 26 leads to a source of oil supply. When oil is forced by a pump or other device into the ports 20 leading into the throat or constricted portion of the Venturi tube 17, as the steam traveling at high velocity passes the inner orifices of the ports 20, finely divided particles of oil are caught up and carried along in the form of spray in the traveling steam for uniform distribution throughout the mass thereof and correspondingly uniform engagement with the working surfaces with which the steam comes into contact.

It will be seen that the check valve structure shown at 23 in Figure 2 of the drawings provides a means for preventing the return of oil fed into the apparatus or the back flow of steam when the oil pump is not operating, the conical valve member 27 being forced toward its seat 28 by a spring for this purpose. A cover cap member 29 is provided for normally covering the valve parts and protecting them from dust and the like.

A valve member 30 is provided which is in the form of a plug member and can be removed bodily from its seat or withdrawn a slight amount to permit oil from the channel 24 to pass through the port 31 and through a drip opening 32 to thereby indicate that oil is being forced through the lubricating system by a pump or other feeding device.

In like manner a plug 33 is provided which can be removed bodily to drain the adjacent chambers or the oil remaining in the system, in the event that the engine ceases to operate, can drain by gravity into the feeding tubes 14, 15 and 16 as will be seen.

The Venturi tube 17 has screw-threaded relation at 34 with the frame member 18 and can be readily removed therefrom or placed therein as desired.

In order to prevent the flowing of steam from the cylinder or associated parts in a reverse direction into the manifold 13, a valve seat is provided at 35 in the member 19 against which ball valve member 36 is forced in the upward movement of steam through the Venturi tube section to thereby check the flow of steam into the manifold. In the reverse or normal direction of flow of the steam from the manifold into the cylinder the ball valve 36 descends and rests upon a set of prongs or lugs 37 formed on the upper extremity of the Venturi tube member 17. It will be seen that the steam passes freely between the prong members and around the ball valve 36 into the Venturi tube. The

area for the steam flow around the ball is at all places equal to the area through partition 19 and is much greater than that of the throat and of the constricted section of the Venturi tube.

While for convenience in explaining the invention I have referred to the application of the improved lubricating system to the steam cylinder and associated parts of a locomotive engine, it will be clear that the lubricating apparatus shown and described is applicable to any apparatus wherein a pressure fluid is used and comes into contact with relatively movable parts. It will also be understood that the atomizing apparatus may be used as a single unit where required. The atomizing device may also be applied immediately at the point at which oil is to be introduced into the fluid chamber, instead of being attached to a manifold spaced apart therefrom as in the manner herein described. In such a case a steam pipe would be individually used for each atomizer. It will be understood that oil may be introduced into the atomizer structure primarily by means of a mechanical pump or hydrostatic lubricator, at which point it is converted into the atomized or finely divided form by the moving column of steam with which it engages.

Preferably the discharge end of the inlet steam pipe 38 leading from the boiler into the manifold 13 is provided with a screen member 39 which will prevent the passing of material into the atomizers which would tend to clog the same and prevent the operation thereof.

It will be understood that numerous variations and modifications may be made in the construction shown and described without departure from the invention as defined in the appended claims.

What I claim is:

1. In a device for introducing lubricating oil into a steam chamber, a source of steam under pressure, a steam chamber mounted beneath the level of the source of steam under pressure, a conduit leading downwardly from the source of steam pressure to the steam chamber, a unitary Venturi tube mounted in said conduit, the conduit forming an annular chamber enclosing the restricted throat section of the Venturi tube, ports leading from the annular chamber through the walls of the restricted portion of the Venturi tube, upstanding lugs formed on the upper extremity of the Venturi tube, a ball member normally mounted on the upper ends of the lugs, a seat formed in the conduit above the ball member, an oil feeding conduit member mounted in a vertically disposed position at one side of the steam conduit, a spring-pressed valve normally closing the upper end of the oil feeding conduit, a chamber enclosing the valve and adapted to receive oil forced through the valve structure under pressure, 125

and an oil feeding passageway leading diagonally downward from the valve chamber to the chamber enclosing the throat of the Venturi tube.

- 5 2. In a device for introducing lubricating oil into a region of fluctuating pressure, a vertical Venturi tube having a bore tapered in both directions from a central region of minimum diameter and an oil inlet bore extending diagonally downward into the vertical bore at its region of minimum diameter and a check valve preventing flow of oil in reverse directions.
- 10 3. The combination with a steam engine and a main steam supply conduit of a lubricating system comprising an auxiliary relatively small pipe line leading from the steam supply to the steam engine, a Venturi tube introduced in said pipe line having a vertical bore tapered gradually in both directions from a central region of minimum diameter and having a plurality of oil inlet bores extending diagonally downward into the vertical bore at its region of minimum diameter.
- 15 20 4. In a device for introducing lubricating oil into a steam chamber, a source of steam under pressure, a steam chamber, a conduit from the source of steam pressure to the steam chamber, a Venturi tube forming a part of said conduit and through which all the steam carried by said conduit passes, an oil reservoir, a port connected to said oil reservoir and leading through the wall of the restricted portion of the Venturi tube, a check valve to prevent back flow through the Venturi tube and a check valve to prevent back flow of oil through the oil port, substantially as described.
